UNITED STATES PATENT OFFICE.

HENRY LEWIS CHARLES, OF BUTTE, MONTANA.

REVERBERATORY SMELTING-FURNACE.

SPECIFICATION forming part of Letters Patent No. 608,837, dated August 9, 1898.

Application filed June 26, 1896. Serial No. 597,059. (No model.)

To all whom it may concern:

Be it known that I, HENRY LEWIS CHARLES, of Butte, in the county of Silver Bow and State of Montana, have invented new Improvements in Reverberatory Smelting-Furnaces, of which the following is a full, clear, and exact description.

The invention relates to reverberatory smelting-furnaces; and its object is to provide a new and improved apparatus for conveniently and quickly removing the molten floating slag from the molten metal in a very economical manner and without danger of chilling the molten metal.

This invention consists in a furnace of such construction as will be fully described hereinafter and defined in the claim.

Reference is to be had to the accompanying drawings, forming a part of this specification, in which similar characters of reference indicate corresponding parts in all the figures.

Figure 1 is a side elevation of the improvement. Fig. 2 is a sectional plan view of the same on the line 2 2 of Fig. 1, and Fig. 3 is a transverse section of the same on the line 3 3 of Fig. 2.

The improved apparatus is provided with a hearth A, which may be composed of a metal base-plate supporting a bed of fire-brick. The hearth contains the molten metal B and the slag B', likewise in a molten condition and floating on the top of the molten metal B. The latter can be withdrawn from the hearth in the usual manner through the matte tap-hole C, and the slag B' is adapted to be driven through a slag-hole D, formed in one of the walls of the hearth and in a plate attached to said wall, as is plainly indicated in Figs. 2 and 3. The floating molten slag B' is driven into this slag-hole D by the force of an air blast or blasts issuing through the twyers E, held approximately horizontal in the wall of the hearth A, located opposite the one containing the slag-hole D.

The discharge ends of the twyers E are somewhat above the level of the molten metal B, so as to cause the air to act directly on the molten slag B' to drive the same laterally into and through the slag-hole D. As shown in Fig. 2, the twyers E point toward the slag-hole D to produce the desired result.

The several twyers E are connected with an air-chamber F, provided at one end with

a safety-valve G and connected at its other end with the blast-pipe H for delivering the usual blast to the furnace. The blast-pipe H is connected with a blower I or other suitable source of air-supply, and the connection between the pipe H and the chamber F is controlled by a valve J, contained in the chamber F near the pipe H. A second valve K is held in the air-blast pipe H, below the entrance of the chamber F into the said pipe H, so that when the said valve K is closed and the valve J is opened the air-blast passes from the pipe H into the chamber F and from the latter through the several twyers E upon the molten slag to drive the same to and through the slag-hole D, as previously explained.

It is understood that it requires but a few minutes to remove the slag from the molten metal, and as soon as this has been accomplished the valve J is closed and the valve K is again opened to permit the air to pass over its regular course to the furnace.

Doors e, respectively rolling in guideways e', are respectively provided for the twyer-openings, and by these means the twyer-openings may be closed when the twyers are withdrawn.

The hearth A, with its sides bulging or curved outward, enables the twyers E to be arranged properly with reference to the slag-hole. This arrangement is such that the twyers extend radially with reference to the slag-hole and directs the slag in one gradually-contracting sheet through the slag-hole.

Having thus fully described my invention, I claim as new and desire to secure by Letters Patent—

A reverberatory smelting-furnace, having an elongated hearth, one of its side walls having a centrally-located slag-discharge orifice, and the other of said side walls having a plurality of twyer-openings, and a series of twyers respectively projected through said twyer-openings, the twyers being disposed angularly to each other and each radially from the slag-discharge orifice, so that the blast from the twyers is directed to and concentrated at the slag-discharge orifice.

HENRY LEWIS CHARLES.
